UNITED STATES PATENT OFFICE.

WILLIAM KARPEN, OF BROOKLYN, NEW YORK.

SIGN-BOARD.

1,132,097.

Specification of Letters Patent. Patented Mar. 16, 1915.

Application filed June 3, 1914. Serial No. 842,546.

To all whom it may concern:

Be it known that I, WILLIAM KARPEN, a citizen of the United States, and residing at Brooklyn, in the county of Kings and State 5 of New York, have invented certain new and useful Improvements in Sign-Boards, of which the following is a specification, such as will enable those skilled in the art to which it appertains to make and use the 10 same.

This invention relates to sign boards, display and like devices, and the object thereof is to provide an improved device of this class which is particularly designed to serve 15 as a sign board and which involves detachable letters any desired number of which may be employed and whereby any preferred sign may be quickly and easily placed on the board, or the form of a sign changed, 20 and with this and other objects in view the invention consists in a device of the class specified, constructed as hereinafter described and claimed.

The invention is fully disclosed in the 25 following specification, of which the accompanying drawing forms a part, in which the separate parts of my improvement are designated by suitable reference characters in each of the views, and in which:—

30 Figure 1 is a front view of a sign board involving my invention; Fig. 2 a vertical section on the line 2—2 of Fig. 1; Fig. 3 a view similar to Fig. 2 but showing only a part of the board and showing said part on 35 an enlarged scale; and, Fig. 4 a perspective view of one of the sign letters or characters that I employ.

In the practice of my invention, I provide 40 a frame *a* which is preferably rectangular in form and comprises top and bottom members *a*², side members *a*³ and a back or body portion *a*⁴, said back or body portion being set into the frame in the form of a panel and being secured therein by brads or nails 45 *b* in the usual manner, and the sides and top and bottom members of the frame are provided with inwardly directed flanges *a*⁵ between which and the back or body portion *a*⁴ are narrow spaces *a*⁶ in which are secured

transverse, flexible strips *c*, any desired number of which may be employed, and beginning with the second strip from the bottom, the bottom edge of each of said strips is overlapped by the bottom edge of the strip thereunder, as clearly shown in Figs. 2 and 50 55 3. I also provide a plurality of letter tabs *d* which may be composed of cardboard or any suitable sheet metal material and which are of predetermined length, and the tops of which are provided with downwardly and 60 65 backwardly folded flange or hook members *d*². The letter tabs *d* are of such length that when the flange or hook member *d*² is passed over the top edge of one of the strips *c* the bottom end of said tab may be passed 70 back of or under the top edge of the second transverse strip thereunder as clearly shown in Fig. 1, and when said letter tabs are placed in position they may be moved back and forth, or adjusted transversely of the 75 board and, in practice, any desired sign may be spelled out on the board by means of said letter tabs.

The letter tabs are not necessarily of the 75 length shown whereby said tabs overlap two of the strips *c*, but this length of said tabs is preferred for the reason that it facilitates the manipulation thereof especially when the sign board is a small one, and the strip *c* comparatively narrow in transverse 80 section.

A sign board made in this manner may be used for various kinds and classes of display work as well as for a sign board, and said board and the strips *c* may be made of 85 any preferred material and of any desired dimension, and when the letter tabs *d* are placed in the desired position they will remain therein and can only be removed by hand. 90

Having fully described my invention, what I claim as new and desire to secure by Letters Patent, is:—

A sign board provided with transverse flexible strips, the bottom edge of each of 95 said strips being overlapped by the top edge of the strip therebelow, and letter tabs provided at the top thereof with backwardly

and downwardly directed hook members adapted to engage the top edge of one of said strips, the lower ends of said letter tabs being adapted to be passed beneath the top edge of another of said strips below that which is engaged by the top thereof.

5 In testimony that I claim the foregoing as

my invention I have signed my name in presence of the subscribing witnesses this 1st day of June 1914.

WILLIAM KARPEN.
